(57) **CLAIM**

The ornamental design for a bicycle basket, as shown and described.

DESCRIPTION

FIG. 1 is a front perspective view of a bicycle basket showing my new design invention;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front perspective view of the bicycle basket mounted on a bicycle.

The circular features and the bicycle shown in broken lines form no part of the claimed design.
